WEED PULLER

Andrew Senchak, Taylor, Mich.
(8615 Evergreen, Detroit, Mich. 48228)

Filed Jan. 19, 1966, Ser. No. 681

Term of patent 14 years

(Cl. D35—2)

Portions are shown broken away in FIGS. 1 and 2 to show indeterminate length.

I claim:

The ornamental design for a weed puller, as shown and described.
